CLAIM

We claim the ornamental design for a mouse and adapter, as shown and described.

DESCRIPTION

FIG. 1 is a perspective view of an embodiment of the mouse and adapter, showing only the adapter;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

Broken lines are for illustrating portions of the mouse and adapter which form no part of the claimed design.
